HERBERT MARSHALL STURGIS, OF KANSAS CITY, MISSOURI, ASSIGNOR
OF TWO-THIRDS TO IVAN H. SHOEMAKER AND F. E. WEAR, OF
KANSAS CITY, MISSOURI.

AUTOMATIC DROP-FIXTURE.

SPECIFICATION forming part of Letters Patent No. 755,328, dated March 22, 1904.

Application filed February 3, 1903. Renewed January 25, 1904. Serial No. 190,617. (No model.)

To all whom it may concern:

Be it known that I, HERBERT MARSHALL STURGIS, of Kansas City, Jackson county, State of Missouri, have invented certain new and useful Improvements in Automatic Drop-Fixtures, of which the following is a full, clear, and exact description, reference being had to the accompanying drawings, forming a part hereof.

10 My invention relates to automatic drop-fixtures, which are especially adapted to window-shade adjusters; and it consists of the novel construction, combination, and arrangement of parts hereinafter shown, described, and claimed.

15 Although I have shown my invention to be used as a window-shade or curtain-adjuster, it may be advantageously employed for other purposes—as, for instance, for adjusting maps, advertising matter, charts, display devices in stores, &c.

In the drawings, Figure 1 is a front view of my invention, showing the same applied underneath the top of the window-casing, the shade being swung by my invention and lowered, exposing a portion of the top window-pane. Fig. 2 is a side view of the operative portion of my invention. Fig. 3 is a bottom view. Fig. 4 is a sectional view taken on the line 4-4 of Fig. 2. Fig. 5 is a section taken on the line 5-5 of Fig. 2. Fig. 6 is a detail perspective view of the elongated pawl and the pivoted frame which operates the same. Fig. 7 is a detail view of the cord-drum, showing the openings for holding the cord. Fig. 8 is a detail perspective view of the adjustable shade-roller bracket or support. Fig. 9 is a perspective view of my invention. Fig. 10 is a sectional view taken on the line 10-10 of Fig. 9.

40 Referring to the drawings, 1 indicates a plate which is stamped from a single piece of metal, which plate is adapted to be secured to the window-frame by means of screws or any suitable device which may be inserted 45 through the holes 2. Said plate is provided with an integrally-elongated flange 3, integral

perforated ears 4, and an integral perforated ear 5, the purpose of the ears 4 and 5 and the elongated flange 3 being more fully hereinafter described. The integral elongated flange 3 is also provided with perforations 6, for the purpose hereinafter described. The plate 1 is provided with a right-angular projecting portion 7, having a perforation 8, and is also provided with a similar right-angular projecting portion 9, having an elongated slot 10 and also a hole 11 in alignment with the perforation in the ear 5. Mounted in the perforations in the ears 4 and in the perforations 6 in the elongated flange 3 are two right-angular bent rods 12, the vertical ends of said rods being connected by a plate 13.

14 indicates two small sheave-pulleys, which are rotatably and slidably mounted on the rods 12 between the plate 13 and the flange 3. One of the rods 12—that is, the one on the right in Fig. 9—has mounted thereon between the elongated flange 3 and the perforated ear to the right in said figure a skeleton frame 15. This skeleton frame 15 has its terminal portions 16 and 17 provided with perforations 18, through which the rod 12 is adapted to be inserted. In other words, the terminal portions 16 and 17 of the skeleton frame 15 are pivotally mounted on the rod 12. The function of this pivoted skeleton frame 15 will be more fully hereinafter described.

19 indicates the drum-rod, which is adapted to be slidably mounted in the perforation 8 and the slot 10. Said rod is of sufficient size relative to the size of the perforation 8 and the slot 10 as to freely rotate and slide in said perforation and slot, which act as supporting-bearings for said rod. Rigidly mounted on said rod is a cord-drum 20, said cord-drum being hollow and cylindrical and provided on one end with a flange 21 and on the opposite end with an integral ratchet-wheel 22. Said drum is also provided with fastening means 90 for the cords which support the shade-bracket, which means consist of circular holes 23, into which communicate narrow slots 24. As heretofore stated, the cord-drum 20 is rigidly fixed

and secured to the rod 19—that is, it has no movement independent of said rod.

25, Fig. 10, indicates a rod which is mounted in the perforation in the ear 5 and the perforation 11 in the portion 9. Said rod answers as a pivot for the elongated pawl 26, and said elongated pawl 26 has two perforated ears 27, into and through which the rod 25 passes, thereby pivoting said ears, and consequently 10 the pawl 26, on said rod. One of said perforated ears 27 is provided with an inclined face 28, Fig. 6.

The skeleton frame 15 is provided with a projecting shoulder 29, and said shoulder is 15 provided with a contact-face 30, which contact-face is adapted to engage with the face or edge 28 of the ear 27. Said projecting shoulder 29 when moved in a direction toward the right in Fig. 9 or 6 rides over the ear 5 and strikes the 20 face 28, and consequently will elevate the engaging edge 31 of the elongated pawl 26. In other words, the object of the projecting shoulder 29, with its engaging face 30, is to act on the face 28 of the ear 27 for elevating and lowering the elongated pawl 26. In other words, if it is necessary to elevate the engaging edge 31 of said pawl it is only necessary to push the frame 15 to the right. When said frame is 25 pushed to the right, the shoulder 29 is elevated, which comes in contact with the face 28 of the ear 27, thus elevating the pawl. When said frame 15 is moved to the left, releasing the shoulder 29 from the face 28, the pawl will drop by its gravity. The movement to 30 the right of said frame 15 disengages the pawl, and the movement to the left will allow the pawl to drop by its own gravity, thereby effecting an engagement with the ratchet-wheel 22, carried by the drum 20. The frame 15 is 35 provided with a hole 32, through which the operating-cord 33 is adapted to pass, and also with a hole 34 for the insertion of the operating-cord 33 should the fixture be applied to the front of the window-casing in place of underneath, as shown and described in this application.

35 indicates the shade-roller bracket, which is composed of two sections 36 and 37. Said sections are held together by means of a band 50 38, which is provided with a set-screw 39. The section 36 is cylindrical, and the section 37 is adapted to be inserted in said section 36, and the band 38 is rigidly fixed to the section 36. By means of this construction the shade-roller bracket 35 may be adjusted to any length 55 of shade-rollers. The section 36 is provided with an arm 39', having a square aperture 40 for the insertion of the angular lug of the shade-roller, and the section 37 is provided 60 with a circular opening 41 for the round lug of the shade-roller.

42 indicates a U-shaped piece of metal provided with perforated ears 43, in which the section 37 is adapted to be inserted. Said U- 65 shaped piece of metal 42 is pivotally mounted

on the section 37, and to said U-shaped piece of metal one end 44 of one of the shade-roller-supporting cords 45 is secured.

46 indicates a sheave-pulley on which the cord 45 is mounted, and said sheave-pulley 46 70 is mounted in a bracket 47, said bracket 47 being pivotally secured to a bracket 48. The bracket 48 is located to the right in Fig. 1 and is secured underneath the window-casing. To the left in Fig. 1 is a similar sheave-pulley 75 49, mounted in a bracket 50, which bracket 50 is pivotally secured to another bracket 51, and on the sheave-pulley 49 the other shade-supporting cord 52 is mounted, the lower end of the same being secured to the section 80 36 of the adjustable shade-roller-supporting bracket 35.

As heretofore stated, 45 and 52 indicate the cords by means of which the shade-roller bracket is supported. The lower ends of said 85 cords are secured to the shade-roller bracket and are mounted to pass over the sheave-pulleys 46 and 49. They are also adapted to pass over the rotatable and slidably-mounted sheave-pulleys 14. 90

I will now proceed to describe how the cords which support the adjustable shade-roller-bracket are secured to the cord-drum 20. By referring to Fig. 7, wherein the construction of the cord-drum is shown, the holes 23 95 and slots 24 are designed for the purpose of affixing two of the ends of the cords to support the adjustable shade-roller bracket. In order to secure the cords to the drum, it is necessary to tie a knot in the ends of the cord, 100 and it will be noticed in this connection that the two openings to the left in Fig. 7 are to receive the ends of the cords 45 and 52, which support the shade-roller bracket. The opening to the right in said Fig. 7 is to receive 105 one end of the cord 33, which is the operating-cord. After knots have been tied in the ends 110 the knots are inserted through the holes 23, and a portion of the cords are then pushed back into the slots 24, the slots 24 being narrower and of smaller dimensions than the holes 23, and the knots being of sufficient size to be 115 barely threaded through the holes 23 will not slip out of the slots 24. It will be seen from this construction that the knots are located on the inside of the drum, thus leaving the exterior of the drum unobstructed. When the ends of the cords 45 and 52 have been attached to the drum 20, as described, and from the fact that the rod 19 is rotatably and slidably mounted in its bearings, and when said 120 cords are wound on the drum 20 when the drum is rotated so as to wind the cords thereon, said cords will produce two single coils 54 and 55, the cord 45 forming the coil 54 and the cord 52 forming the coil 55. 125

As heretofore stated, 33 indicates the operating-cord, one end of which is secured in the slot 24 to the right in Fig. 7 after the manner of the ends of the cords 45 and 52, 130

as heretofore described. After the end has been secured in said slot the free end is brought down through the hole 32 of the frame 15. It will be noticed in this connection that said cord is attached to the drum after the other two cords 45 and 52 have been wound up or coiled on the drum, as shown in Fig. 2. The coils 54 and 55 are wound and unwound on the drum in the same direction, and the coil formed from the operating-cord 33 is wound in a different direction. The pulling down on the cord 33 when it is secured to the drum, as hereinbefore stated, has a tendency to rotate the drum toward the operator sufficient only to permit to be released the edge 31 of the elongated pawl 26 from the ratchet-teeth 56 of the ratchet-wheel 22. The pulling of said cord to the right will release the pawl from the teeth, as heretofore described.

I claim—

1. In an automatic drop-fixture of the character described, a plate stamped from a single piece of sheet metal and provided with an integrally-elongated perforated flange 3, integral perforated ears 4 and 5, right-angular rods mounted in said ears and flange, a frame 15 provided with a projecting shoulder 29 pivoted to one of said right-angular rods, a rod 30 25 carried by said plate, and an elongated pawl mounted on said rod and provided with a slanting face 28 which is adapted to be engaged by the shoulder 29 when the frame 15 is pushed to the right, whereby said pawl may 35 be operated, substantially as specified.

2. An automatic drop-fixture, comprising a plate stamped from a single piece of metal and provided with an elongated perforated flange 3, perforated ears 4 and 5, portions 7 and 9 40 having a hole 8, slot 10 and opening 11; right-angular rods 12 mounted in perforations in said flange 3 and ears 4, sheave-pulleys 14 carried by said rods, a plate 15 pivoted to one of said rods, a rod 25 mounted in the opening 45 11 and perforated ear 5, a pawl pivoted to said

rod adapted to be elevated when the frame is pushed toward the right, a rod 19 rotatably and slidably mounted in the hole 8 and slot 10, and a cord-drum rigidly fixed to said rod, substantially as specified.

3. In an automatic drop-fixture, a plate 1 adapted to be secured to a window-casing, the same being stamped from a single piece of sheet metal and provided with an elongated perforated flange 3 and perforated ears 4, 55 right-angular rods 12 mounted in said ears and said flange, a plate 13 secured to the ends of said rods for strengthening and holding the same in parallel position relative to each other, and sheave-pulleys 14 rotatably and slidably 60 mounted on said rods and held from displacement thereon by means of said plate 13, and being limited in their sliding movement by said plate and the flange 3, substantially as 65 specified.

4. An automatic drop-fixture, comprising a plate stamped from a single piece of metal and provided with an elongated perforated flange 3, perforated ears 4 and 5, portions 7 and 9 having the hole 8, slot 10 and opening 11; 70 right-angular rods 12 mounted in perforations in said flange 3 and ears 4, a plate 13 for holding the ends of said rods 12 in parallel alignment, sheave-pulleys 14 carried by said rods and having their adjustable movement limited 75 by the flange 3 and the plate 13, a plate 15 pivoted to one of said rods, a rod 25 mounted in the opening 11 and perforated ear 5, a pawl pivoted to said rod and adapted to be elevated when the frame is pushed toward the right, a 80 rod 19 rotatably and slidably mounted in the hole 8 and slot 10, and a cord-drum 20 provided with tapering slots, rigidly fixed to said rod, substantially as specified.

In testimony whereof I affix my signature in 85 presence of two witnesses.

HERBERT MARSHALL STURGIS.
